MECHANISM FOR PROCESSING VEGETABLE FIBERS

Bruce Armstrong, Saginaw, Mich., assignor to Jackson & Church Company, Saginaw, Mich., a corporation of Michigan

Application August 22, 1952, Serial No. 305,774

6 Claims. (Cl. 19—5)

1

This invention relates to means for processing vegetable fibers and particularly to a type thereof involving a pair of rotatable plates having teeth extending into a zone intermediate said plates.

In a method for separating the fibers of vegetable materials from each other and for separating the long fibers, otherwise known as "bast" fibers, from pith or parenchyma, as described in detail in my co-pending application Serial No. 297,078, filed July 3, 1952, there is required means by which a bending moment is applied to a section of the material being so treated and by which said bending moment is applied repeatedly and rapidly. In one preferred means for applying said bending moment to said vegetable materials, there is utilized a pair of plates rotating with respect to each other, said plates being slightly spaced apart and each having a plurality of teeth thereon extending into an annular space, or processing zone, defined therebetween. Thus, when the vegetable materials are fed into the center of said annular space and permitted to move outwardly toward the periphery thereof, the teeth extending from one of said plates engage said vegetable materials and bend the same against the teeth of the other of said plates whereby the necessary bending is applied repeatedly and rapidly and the disconnecting of said fibers from each other and from the pith portions of the vegetable material is effected rapidly and accurately.

In the provision of said plates, and the arrangement of teeth thereon, there has been present in plates designed for related types of machines a number of characteristics which render such plates somewhat ill-suited for carrying out the method presently under consideration. Accordingly, it was desired to provide a plate and tooth design by which a high degree of bending of the vegetable material would be obtained, by which a maximum flow of material through the zone occupied by said teeth would be obtained and yet a design according to which a plate could be made rapidly and relatively inexpensively.

Accordingly, a principal object of the invention is the provision of a pair of plates adapted to define an annular processing zone when co-axially positioned and suitable spaced from each other and which plates are provided with teeth extending toward each other for engaging and bending vegetable material fed therebetween.

A further object of the invention is to provide a device, as aforesaid, wherein the bending can be carried out accurately and efficiently and with a minimum of breakage or cutting of the fibers of said vegetable material.

2

A further object of the invention is to provide a device, as aforesaid, which can be manufactured rapidly and efficiently.

5 A further object of the invention is to provide a device, as aforesaid, which will permit a maximum flow of material through the processing zone.

10 A further object of the invention is to provide a device, as aforesaid, which will be strong and sturdy and not readily subject to breakage.

A further object of the invention is to provide a device, as aforesaid, wherein a tooth can be readily replaced in the event that breakage or damage does occur.

15 A further object of the invention is to provide a device, as aforesaid, wherein teeth of different designs may be inserted into a given plate.

Other objects and purposes of the invention will be apparent to persons acquainted with apparatus 20 of this general type upon a reading of the following disclosure and inspection of the accompanying drawings.

In the drawings:

Figure 1 represents, somewhat schematically a 25 view of central vertical section of a machine to which the plates of this invention are applied.

Figure 2 represents a top view of the lower of said two plates.

Figure 3 represents a top view of the upper of said two plates.

30 Figure 4 is a section taken on the line IV—IV of Figure 2.

Figure 5 shows an alternate tooth structure.

Figure 6 shows a further alternate tooth structure.

35 Figure 7 is a section taken on the line VII—VII of Figure 6.

Figure 8 shows a further modified tooth design taken in central vertical section.

In carrying out the objects and purposes above set forth I have provided a pair of plates adapted for defining a processing zone when co-axially positioned and suitably spaced apart and provided with a plurality of axially extending teeth, each thereof extending into said zone defined between said two plates. Where, as is usual, one of said plates has an opening in its center for the feeding of material therebetween, the zone into which said teeth extend and in which the vegetable material is processed is an annular zone as indicated in the figures. The teeth are preferably round and extend through said plate from the respectively remote faces of each thereof.

Looking at said plates and tooth structures now in more detail there is shown in Figure 1 a pair 55 of plates 1 and 2 which in this embodiment may

be taken to be positioned in vertically spaced horizontal planes. The upper of said plates is for illustrative purposes assumed to be affixed to the frame 3 of a machine and the lower of said two plates is mounted on the spindle 6 which is supported by suitable bearings 4 and 5, and driven by any conventional means, not shown. It will be understood, of course, that this somewhat arbitrary section of specific operating details is for illustrative purposes only and is not to be construed as limiting. Heat exchange means 7 may be provided if desired.

Referring now to the lower plate 2 in detail there is shown a plurality of substantially round pins on teeth 10. As best shown in Figure 4, each of these pins has a body portion 11 which is press fitted into an opening 12 in said plate. The lower side of said pin has a head 13 formed thereon for engaging a counter-bore in the lower surface of said lower plate and at the upper end of said pin there is provided a substantially cylindrical shank 14 which is preferably, for reasons appearing hereinafter, formed with a diameter slightly smaller than the diameter of said body portion.

Referring now to Figure 2, it will be observed that, as indicated by the broken line A, said pins 10 are arranged in said plate in radially spaced rings, and the circumferential spacing of said pins is such as to arrange said pins, as indicated by the line B in Figure 2, in substantially spiral rows, said rows being defined by arcs struck from centers of which one is indicated by the point C. Point C is positioned intermediate the center of the lower plate 2 and the periphery thereof and is offset circumferentially with respect to all radii of the plate passing through any of the teeth in row B. The amount of such offset and the radius of the arc B will be selected so as to approximate the vector-resultant of the radial and tangential velocities of the material to be processed at three or more radii and to provide a smooth curve drawn through these vectors. The teeth or pins are located at the intersection of arc B and a series of concentric circles A chosen, as shown in Figures 2, 3 and 4, to gradually reduce the bending span as the periphery is approached. Thus, a somewhat spiral path is provided from the central zone of said lower plate to the periphery thereof, as illustrated by the shaded area D in Figure 2. The purpose of this arrangement will appear hereinafter.

Turning now to Figures 3 and 4, for a similar showing of the structure of the upper plate, it will be seen that similar teeth are similarly arranged in said upper plate. Said teeth are similarly constructed and are similarly affixed. The arrangement of said teeth in circumferential and radially spaced rows is generally similar to that in the lower plate shown in Figure 2, and said teeth are arranged circumferentially with respect to each other in any respective ring to provide a path indicated by the shaded zone E. It will be noted that said shaded zone E curves in the opposite direction from the zone D of the lower plate shown in Figure 2.

As will appear more clearly after a description of the operation of the apparatus, the circumferential offset of any given row, as the row 18 (Figure 2), with respect to the adjacent radially inner row, as the row 19, is in such a direction that the paths indicated by the shaded areas D and E, and their several counterparts, curve for each plate in the direction that material is urged by the teeth of the other plate. The radially

inner faces of both plates may preferably diverge to provide a throat 17 for the easier reception of chunks or bundles of unseparated fibers.

In the stationary plate the only energy present is that imparted to the material by the teeth of the rotating plate. Hence, the distance between the teeth, measured on any concentric circle, is greater in the stationary plate than in the rotating plate in order to not unduly retard the progress of the material through the plate. Extra teeth 24, intermediate the teeth located by the intersection of arcs B with only the outermost of the concentric circles A, are provided in the rotating plate. It is intended to control the volumetric capacity of the apparatus by reducing the discharge area and thus impeding too free a discharge of material, without the necessity of reducing the distance between the plates, that is, the gap indicated in Figure 1. This permits securing a high capacity from the apparatus without danger of burning caused by friction between the plates and the material. On some materials having high resistance to heat damage, low coefficients of friction or capacity to break up readily, these intermediate teeth may be omitted.

On the stationary plate, similar intermediate teeth 25 are similarly provided in the two outermost concentric circles because the inherently high centrifugal force developed by the high rotative speed of the rotating plate provides sufficient impetus to keep the material moving through without danger of burning. One or both rows may likewise be omitted here on such materials as indicated above.

As alternate construction, reference is made to Figure 5 wherein there is shown a slant type of tooth capable of effecting certain additional functions. By using this tooth, the clearance between teeth may be readily adjusted when said teeth on one plate are moved axially toward or away from the teeth of the other plate. The reduction in diameter of the shank of the tooth with respect to the body part of the tooth, in both this form of tooth and that shown in Figure 4, is to provide a slight clearance between said teeth under all conditions and thereby to permit ordinary manufacturing errors in the positioning of said teeth to be accommodated. As said plates, fitted with teeth of the Figure 5 form, are moved axially toward and away from each other it will be apparent that the spacing between said teeth may be readily adjusted very accurately and thereby the equipment rendered capable of performing operations of various types, it being borne in mind that for carrying out the method as above indicated and described in detail in my co-pending application Serial No. 297,078, filed July 3, 1952, it is necessary that the teeth effect only bending of the fibers and do not effect any cutting thereof.

Another type of tooth is illustrated in Figures 6 and 7. In this tooth, both the forward and rearward edges are rounded in the same manner as the cylindrical teeth shown in Figure 5, but the tooth is sufficiently elongated as to provide substantial support at the trailing side of each tooth. This is for the purpose of enabling the tooth to be materially longer than might otherwise be permitted by the round type of tooth or it may permit the tooth to be somewhat thinner than would be possible with a round type of tooth and thereby the teeth may be set relatively close together for imposing bending moments on the fibers of relatively short lengths.

As shown by the phantom lines in Figure 6, the

manner of fastening this type of tooth into place in a given plate may be similar to that provided for the teeth of Figure 4 or, by the use of separate fastening elements, indicated at 15 in Figure 8, it is possible to fasten sets of elongated teeth to the opposed surfaces of the same plates as illustrated for use with the round teeth.

Operation

In operation, it will be assumed that the upper plate is stationary and the bottom plate is rotating in the direction indicated by the arrow in Figure 2. It will be understood, however, that the rotation between said plates need only be relative and that either, or both, of them may be in actual motion.

With the lower plate rotating and the upper plate stationary, as above indicated, material to be processed is introduced through the center opening 16 to the inner edge of the processing zone defined between said two plates. As the material is carried into said zone by the air stream drawn there-through by centrifugal force, it first enters the throat 17 and is engaged by the relatively widely spaced inner rows of teeth 18 and 19. For illustrative purposes, a particular section of vegetable material may be considered to be caught upon the moving teeth 21 and 22 and (Figures 2 and 4) carried thereby against the stationary tooth 23. Said stationary tooth will bend the fiber between the teeth 21 and 22 and as it passes said last named two teeth it will somewhat straighten and be carried by the air current radially outwardly where it will be caught and again bent by other similar sets of teeth.

It will be appreciated that in each case, the actual movement of a given section of vegetable fiber will be the resultant of its radial motion and the tangential motion imparted to it by the teeth, as the teeth 21 and 22, of the movable lower plate. In view of the relatively high speed of rotation of said movable plate, as 1750 R. P. M., the circumferential motion will be at a much higher rate than the radial motion. In a typical instance, with plates of 28 inches diameter and having a 15 inch opening through the upper plates, a given section of vegetable fiber may be expected to travel some 8 feet circumferentially while it is traveling approximately 6½ inches radially. Thus, it will travel throughout in a relatively tight spiral, of substantially Archimedean nature, starting with a relatively open spiral and progressively becoming tighter as the section of vegetable material moves into the radially outer portion of the processing zone where the circumferential speed becomes relatively greater.

However, the outward progression of the given section of material will not be in a perfectly smooth spiral but rather it will move somewhat stepwise by moving from one circular path to the next outer circular path through the open zones of which one is indicated by the shaded area D. Thus, the outer progression of material will largely take place through and along the paths of said open areas. These open areas permit a large quantity of material to move through the apparatus and the equipment is thereby provided with capacity for handling a large quantity of material.

Accordingly, a device has been provided capable of accomplishing the objects and purposes above set forth.

While certain specific embodiments of the invention have been here selected for illustrative purposes, it will be recognized that the principles herein disclosed are substantially broader than said specific embodiments and hence the claims hereinafter should be interpreted accordingly, excepting as said claims by their own terms expressly provide otherwise.

I claim:

1. In a device for repeatedly bending a quantity of fibrous vegetable material, the combination comprising: a lower circular plate and an upper circular plate, said plates being co-axially positioned in spaced and parallel relationship with each other, said plates being each adapted for engagement with supporting means and at least one of said means being capable of rotating one of said plates with respect to the other of said plates; a plurality of teeth on each of said plates, the teeth affixed to each of said plates extending toward the other of said plates and at least a portion of the teeth of one plate overlapping a substantially oppositely positioned portion of the teeth of said other plate, said teeth being arranged in concentric circular rows on each of said plates, said rows being each concentric also with the center of said plates and the teeth of each of said rows being arranged circumferentially with respect to the teeth of the respectively adjacent next inner row in circumferential offset relationship, the direction of said offsets for each plate being that direction in which material is urged by the teeth of the other of said respective plates, whereby to define a plurality of spirally arranged channels through said teeth from an inner zone to the outer periphery of each of said respective plates.
2. A device defined in claim 1 wherein each of said teeth is substantially cylindrical in the portion thereof within the zone between said plates.
3. The device defined in claim 1 wherein said teeth extend through the respective plates upon which they are fastened from the respectively remote sides thereof.

4. The device defined in claim 1 wherein said teeth taper convergingly from the respectively opposed surfaces of said plates.

5. The device defined in claim 1 wherein said teeth are arranged in a plurality of spaced rows, each of said rows defined by the arc of a circle whose center is (1) located intermediate the center of said plates and the peripheries thereof and (2) circumferentially offset from all radii of said plates passing through said teeth.

6. The device defined in claim 1 having teeth near the periphery only of a plate and within said spirally arranged channels.
